ATTORNEY

UNITED STATES PATENT OFFICE.

JOHN BURNS, OF CHICAGO, ILLINOIS.

EGG-CARRIER.

SPECIFICATION forming part of Letters Patent No. 315,476, dated April 14, 1885.

Application filed March 11, 1884. (No model.)

To all whom it may concern:

Be it known that I, JOHN BURNS, a citizen of the United States, and a resident of Chicago, in the county of Cook and State of Illinois, 5 have invented new and useful Improvements in Egg-Carriers, of which the following is a specification, reference being had to the accompanying drawings, illustrating the improvements, in which—

10 Figure 1 is a perspective representation of a knockdown egg-carrier embodying my improvement; Fig. 2, a perspective representation of the recessed base, one end and a portion of one side in position as when set up, 15 the other parts being removed. Fig. 3 is a side elevation of the case in a knockdown form; and Fig. 4, a sectional elevation on line x, Fig. 3.

The object of the present invention is to 20 provide better means for storing the straw-board egg-compartments and the partition of knockdown egg-carriers, and to secure the case in its shipping and return forms so that the parts shall not get out of place. I attain 25 this in two-compartment egg-carriers by the use of a recessed base, which serves the purpose of holding the partition and straw-board compartments when the device is in a knock-down form, and to support the sides and ends, 30 and also to form the lower portions of the two egg-compartments where the device is in the form for shipment. The partition is removable, whereby the straw-board partitions when shut together, and thereby lengthened, have sufficient room, and when the device is used for 35 shipment the partition extends from the bottom of the base to the tops of the sides, and consequently with the other parts forms two egg-compartments. The main ends are hinged 40 to the base so as to fold in; but the main sides are removable therefrom and are held to the ends by elbow-catches and tongues and grooves. The cover is fitted on the ends by 45 the same catches which hold the device together in a knockdown shape. By means of this construction the partition and straw-board egg-compartments, being in the recess, are held safely there by the ends, which fold flat on the 50 top of the recessed part. The sides then are placed on the ends, and the cover on the sides, after which the hasps are fastened to the sta-

ples on the base, and the case is ready for shipment. The case shown is intended to hold fifteen dozen eggs on each side of the partition, and each compartment is (inside measure) about twelve inches high, twelve inches long, and twelve inches wide. 55

To prevent the ends from springing out so as to loosen the tongues of the sides when the cover is removed, elbow metal catches z are attached to the sides and bear against the ends, but do not project onto the ends far enough to be in the way of securing the parts in a knockdown form. The recessed base is 60 composed of a bottom board, B, sides F F, and ends E E, secured together by nails or screws in a substantial manner. The inner top edges of the sides F and ends E of the recessed base are rabbeted out to fit reverse 70 rabbets on the lower edges of ends D and sides C. The ends D are hinged to the ends E at P P, so that they may stand upright or lie flat. The sides C are formed with tongues a on their ends to fit into vertical grooves b in 75 the ends D. These tongues and grooves are not new in this case, but are a necessary part of the construction. The ends D are also provided with tongues c on their top ends to engage grooves d, formed in the under sides of 80 the cover A. The main boards D, C, and A to the ends, sides, and cover should be about three-eighths inch thick, and the cleats R S T about the same thickness, and firmly secured together by wrought nails clinched, and, if 85 glue be used, the strength will be largely increased at nominal cost. Pivot-plates N N are secured to the sides C C, and to them loosely are pivoted hasps J J, which engage eyes O O, fastened to the sides F F of the recessed base. The hasps are held on the eyes by means of split spring keys L L, which are attached to the hasps by small chains or wire cord. Pivot-plates H are fastened to the cover 90 A, and they support hasps J, which fasten to 95 eyes K K, attached to the cleats S, the same chains and split spring keys L x being employed to hold the hasps to the eyes, as above described.

Fig. 1 represents the carrier as complete as 100 when used to transport eggs, except one hasp is shown detached from its eyebolt, as when the lid is being removed.

In the knockdown form of the carrier the

ordinary straw-board Stevens compartments *e* are placed in the recessed base and the partition *W* put on the top thereof. The ends *D* are then folded flat down and the sides *C* placed on the top thereof. The cover *A* is then put on the top of the sides and the outside hasps, *J J J J*, are secured to eye-plates *M*, which are attached to the sides *F F* of the bottom, and the carrier is complete for re-shipment.

Having thus described my invention, what I claim as new, and desire to secure by Letters Patent, is—

In two-compartment knockdown egg-carriers, the recessed base *B E F*, in combination with the sides and ends *C D*, constructed as specified, the elbow-catches *z*, the cover *A*, partition *W*, straw-board compartments *e*, and suitable catches, *N H J O M*, as and for the purpose described. 15

JOHN BURNS.
